UNITED STATES PATENT OFFICE.

HARRY C. LOUDENBECK, OF PITTSBURGH, PENNSYLVANIA, ASSIGNOR TO THE
WESTINGHOUSE AIR BRAKE COMPANY, OF WILMERDING, PENNSYLVANIA,
A CORPORATION OF PENNSYLVANIA.

BRAKE-CYLINDER PISTON-PACKING.

1,314,143.

Specification of Letters Patent. Patented Aug. 26, 1919.

Application filed September 21, 1917. Serial No. 192,510.

To all whom it may concern:

Be it known that I, HARRY C. LOUDENBECK, a citizen of the United States, residing at Pittsburgh, in the county of Allegheny and State of Pennsylvania, have invented new and useful Improvements in Brake-Cylinder Piston-Packings, of which the following is a specification.

This invention relates to packing, and more particularly to cupped packing as employed in pistons adapted to work in cylinders.

Piston packing of the above character is ordinarily made of leather and in order to hold the packing tightly against the walls of the cylinder, it is usual to employ a resilient expander ring which is fitted inside of the packing and acts against the packing.

By reason of the increasing scarcity and high price of leather, one object of my invention is to provide a piston packing formed of other material.

Another object of my invention is to provide a piston packing which will have inherent resiliency to press firmly against the cylinder wall and thus dispense with the use of expander rings.

Another disadvantage in the use of leather for piston packing is that it becomes more or less porous to fluids and liquids in service, so that leakage occurs through the packing, and a further object of my invention is to provide a leak proof packing.

In the accompanying drawing; Figure 1 is a section on line 1-1 of Fig. 2 of a piston packing constructed in accordance with my invention; Fig. 2 a plan view thereof; and Fig. 3 an enlarged transverse section of a portion of the packing.

According to my invention, the packing is formed of layers of ground cork with an intermediate layer of fabric, the resulting pile being pressed into the desired cup shape by means of a die mold and press.

The preferred process of making the

packing is covered by my co-pending application Serial No. 192,483, filed September 21, 1917, and consists briefly in providing disks cut from sheets of pressed ground cork mixed with a suitable binder and disks of 50 fabric such as duck or canvas.

The ground cork disks are coated on one side with glue and preferably the fabric disk is also coated with glue. A pile is then made of two ground cork disks with an intermediate disk of fabric and the pile is placed in a die mold where it is formed into the cup shape while the glue remains unset.

The pile is retained in the die mold and is heat treated to set the glue and is then 60 ready for service.

As shown in Fig. 1 of the drawing, the packing comprises a flange 1 which is secured to the piston and a flange 2 which bears against the walls of the cylinder.

The flange 2 is flared outwardly and it has been found that the resiliency given to the packing by the reinforcing fabric layer is ample to maintain the packing tightly against the walls of the piston cylinder, so 70 that it is not necessary to employ an expander ring for that purpose. Furthermore, the packing retains this resiliency throughout the life of the packing.

The fabric of the intermediate layer 3 of 75 the packing is preferably duck or canvas.

The interposition of the fabric layer while reinforcing the cork layers, also prevents breaking of the packing at the bend while being formed as well as in service.

Having now described my invention, what I claim as new and desire to secure by Letters Patent, is:—

A cup shaped piston packing formed from pressed disks composed of ground cork 85 with an intermediate layer of duck fabric.

In testimony whereof I have hereunto set my hand.

HARRY C. LOUDENBECK.
